UNITED STATES PATENT OFFICE

FRANK DESMOND SPRAGUE, OF QUINCY, MASSACHUSETTS, ASSIGNOR TO SPRAGUE SPECIALTIES COMPANY, OF QUINCY, MASSACHUSETTS, A CORPORATION OF MASSACHUSETTS

WINDING MACHINE

Application filed December 17, 1929. Serial No. 414,737.

The present invention relates to winding machines and more particularly to machines for the mass production of coiled articles wound to a predetermined number of turns.

5 One application of this invention is in the manufacture of a certain type of electrical condenser which consists of a composite coil comprising as a rule two metallic strip conductors, separated by interposed layers of 10 paper or other suitable dielectric material.

These condensers, as a rule, are wound from endless rolls of metal foil and paper cut to the proper width, the rolls being so disposed relative to each other that in winding the metal foil and paper layers two or 15 more paper layers are interposed between the two metal foils.

The mandrel is rotated manually or by a motor and the condenser wound to the required number of turns, after which the mandrel is stopped and the paper and metal foil severed from the stock rolls.

All other factors remaining unchanged, 25 the capacity of the condensers is dependent on the length of the wound strips. It is obvious, therefore, that to obtain a predetermined capacity, the number of turns of the condenser have to be maintained with great accuracy. For this purpose winding machines, as a rule, are provided with revolution-counters. When the operator, following 30 the indication of the counter, notices that the required number of turns to which the condenser is to be wound, is approached, he slows down or stops altogether the winding 35 mandrel and by careful rotation thereof completes the winding of the condenser.

It is evident from the foregoing that such 40 procedure not only requires frequent observation of the revolution counter on the part of the operator, and thus not only interferes with and delays or prevents him in his other functions, but also considerably slows down the winding operation due to the required 45 slow and careful winding of the last few turns. Furthermore, even with the greatest care on the part of the operator, mistakes due to the human element, are likely to occur, and as the last turns of the condenser 50 correspond to the diameter of the condenser,

the influence of any mistake in exceeding or falling short of the required number of turns is quite pronounced on the capacity of the condenser. Besides variation in capacity this also may mean considerable waste 55 of material.

It is, therefore, one object of the present invention to provide a mechanism whereby the winding machine, after winding a predetermined number of turns—determined by 60 the setting of the machine—is automatically stopped at exactly the number of revolutions required for the winding of the condenser to its proper capacity.

Furthermore, when the condensers are 65 wound with present-day winding machines, the operator is required to manually sever the metal and paper strips from the stock rolls, and also required when starting a new condenser to bring the paper and metal strips 70 in proper lateral and longitudinal alignment to the winding mandrel. These operations, besides requiring special skill and care on the part of the operator, also considerably reduce the speed of production. 75

It is, therefore, a further object of my invention to relieve the operator of the duties of severing and re-aligning the winding stock and to increase the speed of operation by providing means to automatically sever and 80 re-align the metal and paper strips.

Further objects of my invention will appear as the description progresses.

In the drawings forming part of these 85 specifications,

Figure 1 is a vertical elevation of a winding-machine embodying my invention, as viewed from the operator's position.

Figure 2 is a side elevation of Figure 1, as viewed from the left of the operator's 90 position.

Figure 3 is a front elevation of the driving motor and transmission mechanism.

Figure 4 is a top view of the mechanism 95 illustrated in Figure 3.

Figure 5 is a side view showing the gear and chain transmission means as viewed from the right of the operator's position.

Figure 6 is a side view showing details of the manually operated control lever. 100

Figure 7 is a side elevation of the cut-off and feeding mechanism.

Figure 8 is a plan view of the cut-off mechanism.

6 Figure 9 is a sectional view of the trip-block.

Figure 10 is a side view of the trip-block as viewed from the right of the operator's position.

10 Figure 11 is a perspective view of the carrier frame and associated mechanism.

Fig. 12 is a fragmental side view showing the clamping rolls separated for insertion of new stock.

15 Detailed reference will now be made to the drawings in which corresponding reference numbers designate corresponding parts:

Referring now more particularly to Figs. 1 and 2, the winding-machine there shown

20 comprises a cast-iron bed plate or platen 10, supported by cast-iron legs, 13-13, reinforced by a pair of upper and a pair of lower braces 13a-13a, the lower braces being also tied together by a transversal tie-rod 14.

25 Mounted about the middle of the bed-plate 10 is a vertical spindle carrying frame 11, properly reinforced by a vertical stiffening frame 12 and by ribs 200 the frame being provided with a plurality of bored bosses 30 200a, which constitute bushings of corresponding spindles 15, these spindles being adapted to carry stock rolls a-1, a-2, etc.

In the illustration eight spindles 15-15 are shown corresponding to the eight stock 35 rolls a-1 to a-8. Of these rolls the rolls a-1 and a-5 are rolls of metal foil, while the rest are rolls of paper, and the disposition of the rolls is such that in winding three layers of paper are interposed between the 40 two layers of metal foil.

For proper alignment of the individual layers the spindles 15 are provided with lateral adjustment, effected by means of hand-wheels 16, and when adjusted the 45 spindles are locked in the desired position by locking wheels 17.

Carried on each spindle 15 and secured thereto is a guide-flange 201, having preferably a larger diameter than the maximum 50 diameter of the stock to be wound. The stock rolls are pressed with their inner face against the flange 201 by means of clamping collars 19, slipped over the spindles 15, and secured thereto by means of butterfly nuts 202.

55 For the proper retardation of the stock during the winding, and for the maintenance of its proper tension, I provide for weighted band-brakes 203, suspended either on upper or on lower supporting studs 204, respectively 60 205, which project horizontally from the frame 11. In case of new stock rolls and as long as the original diameter of the roll has not been reduced below a given limit, the brake-band,—as shown for the seven rolls, a-1, a-2 and a-4 to a-8, is suspended on

the upper supporting studs 204. However, when in the course of the winding the diameter of any of the rolls has been reduced below that limit, (as shown for roll a-3), to maintain proper tensioning, the brake-band 203 is removed from its stud 204 and suspended on the corresponding stud 205.

To feed and guide the winding stock from the rolls toward the winding mandrel 25, later to be described, there are provided proper guiding and feeding means. These means comprise carefully ground rotatable rollers 20, their spindles 198 being supported in bushings 207 of bosses 207-a of the frame 11, one guide roller 20 being provided for each of the stock rolls except roll a-4, the disposition of which requires an additional roller 20-a, and roll a-8, disposition of which requires no such roller.

80 After passing rollers 20, the stock strips are carried under individual guide rollers 21, which are similar in construction to the rollers 20, and which are preferably arranged in a bank unit, their spindles 199 being supported in bushings of a common obliquely disposed boss 21-a of the frame 11. From rollers 21 the material is fed over individual fixed guide-rods 208, preferably supported by a common vertically-disposed bracket 209, affixed to the frame 11 by screws 209-a. 85 From the guide-rods 208 the individual strips are fed to a common gathering roller 22 of the roller carrier-frame 88,—later to be described, where the individual strips unite to form a single composite strip.

90 From the roller 22 the composite strip is fed toward and passes between a roller pair 23 and 24 of the roller carrier frame and thence is wound around the mandrel 25.

95 The disposition of the stock is shown for condensers having two layers of metal foil with three layers of paper interposed. It is apparent that by omitting some of the paper rolls the same machine can be used for condensers having less than three layers of paper between the metal foil, and it is also obvious that by increasing the number of spindles, condensers having a larger number of paper and metal foil layers can be wound.

100 It should also be noted that the shown disposition of the stock rolls and guide-rollers provides for a very compact and easily serviceable layout of the winding-machine, whereas the feeding, aligning and braking means insure exactness and proper tensioning of the winding.

105 The driving mechanism is illustrated in Figs. 1 to 5. The driving unit is located on the top of the bed-plate 10 to the right of the frame 11, and in front of the stiffening frame 12, and comprises an electric motor 30, which in operation, is in constant revolution irrespective of intermittent stoppage of the winding. Provided on the motor-shaft 210 is a fly-wheel 31 (see Fig. 4), the right- 110

hand face of which constitutes a hollow cone. Cooperating with the hollow cone to form a clutch mechanism therewith is a coned member 32, carried by a spindle 33, which is slidably supported in a bearing 211. The end of the spindle 33 projects beyond the bearing 211 and carries a pinion 35, which engages a gear 36 supported by means of its shaft 212 in a pedestal bearing 213 mounted on the bed-plate 10.

The shaft 212 also carries a driving sprocket 37, which engages by means of a chain 38, a sprocket 39, provided on a threaded mandrel-driving shaft 50, this shaft being supported on its right end by a pedestal bearing 64 and at its left by a bearing 224 of the frame 11. A fixed idler pulley 40, carried by an idler-arm 41, affixed to the pedestal 64, enables adjustment of the chain 38.

From the above it may be seen that engagement of the clutch member 32 with the corresponding driving member 31, causes rotation of the driving-shaft 50 through the medium of the aforesaid gear and chain transmission.

Disengagement of the clutch members 31 and 32 result in stoppage of the driving shaft 50. To accelerate stoppage a brake-shoe 34 is provided, which engages the outside face of the clutch member 32 when this member is in its disengaged position (as shown in Fig. 4).

I shall now proceed in describing the means for the control of the winding and automatic stop mechanism, details of which are shown in Figs. 3, 4, 6, 9, 10 and 11.

These means comprise the mandrel driving shaft 50, previously referred to, which is threaded throughout its whole length and provided with a handwheel 130. Forming an extension of the shaft 50 is a winding mandrel 25, its winding portion proper being disposed to the left side of the frame 11.

Located below the driving-shaft 50, and supported on its right-hand end by the pedestal 64, and on its left-hand end by a pedestal 63, is a guide-rod 55, below which and also supported by the pedestals 63 and 64 is a threaded latch-rod 54. The rod 54 is slidably mounted whereby a spring 65 disposed in a bore 214 of the pedestal 64 presses against the right-hand end of the latch-rod 54 and tends to force it toward the left.

Carried on the driving-shaft 50 is a trip-block 51, details of which are shown in Figs. 9 and 10. The trip-block consists of a block 51a having a downward extending portion 48. The block 51a is provided with a bore 56 of slightly larger diameter than the driving-shaft 50, and the extension 48 is provided with a bore 55a adapted to receive the guide-rod 55. Located in a longitudinal recess 57, of the block 51, above the bore 56, is a pawl 58, swingedly mounted on a pivot pin 59 and provided with a handle 60. A top plate 215,

provided with an aperture 216 to receive the handle 60, is screwed or otherwise secured to the top of the block 51. The pawl 58 is provided on its free end with a toothed sector 61 adapted to engage the threads of the driving shaft 50. Under the action of a spring 62 suspended under tension on two horizontally extending hooked studs 217 and 218, these studs being anchored in the pawl 58 and block 51 respectively—the pawl 58 normally assumes the position shown in Figs. 9 and 10, whereby it projects with its toothed end into the bore 56 and thereby engages the threads of the shaft 50. However, upon counter-clockwise movement of the handle 60 the pawl 58 is lifted and disengages its toothed sector 61 from the threads of shaft 50.

When the pawl 58 engages the shaft 50 and when the latter, through engagement of the clutch members 31 and 32 is rotated by the motor 30, the trip-block is carried by the shaft 50 toward the right and advances on the shaft the distance of one thread for every revolution of the shaft. The extension 48 being guided by the rod 55 prevents the trip-block 51 from rotating with the shaft 50.

Carried by the latch-rod 54 are two threaded nuts or collars, viz. a stop-collar 52 and a locking-collar 53. The latch-rod 54 also carries at its right-hand end a lever 78, which enables the operator to force the shaft 54 towards the right against the action of the spring 65.

Mounted on the left-hand side of the bearing pedestal 63 is a starting and latching mechanism, details of which are shown in Fig. 6. A latch lever 66 is mounted on a pivot 219, of the pedestal 63, and has three extension arms of which the upper 220 carries on its end the latch-cam 222, the extension 67 forms an operating handle, and the extension 221 serves as an anchor for a latch spring 68. The other end of the spring 68 is anchored in an adjustable screw-hook 69, carried by the plate 10.

It will appear that if the shaft 54 is moved toward the right by means more fully described hereafter, the cam 66 is free to rotate under the action of the spring 68 in a counter-clockwise direction until it comes to rest against a stop-pin 81 projecting from the pedestal 63.

In this position the shaft 54—which under the action of the spring 65 tends to move toward the left—abuts with its end 72 against the face of the cam 222 and is thereby prevented from such leftward movement. Upon depression of the handle 67 in the position shown in Fig. 6, the cam 222 frees the end 72 and thereby allows the shaft to slide toward the left and behind the cam 222, thus preventing the latched lever from returning to its normal position.

Connected to the extension 220 about in the middle thereof is a tie-rod 71 (see Figs. 4 and 130

6) which interconnects the latch 66 with the clutch-member 32 by the following means: The tie-rod 71 is threaded on its portion 80, and carries there adjustably a nut 74 and a locking-nut 74-a. Engaging the tie-rod by means of its bifurcated end 44 is a double-armed clutch-lever 73, 73-a, pivoted to the frame of the motor 30 at 42. A portion 79 of the tie-rod 71 extends beyond the bifurcated end of the arm 73 and is provided on its end with nuts 75 and a washer 77, and between said washer and the bifurcated end 44 there is located a helical compression spring 76, pressing against the arm 73. The arm 73-a of the clutch-lever engages by means of a suitable joint 43 the shaft 33 of the clutch-member 32.

To start rotation of the winding mandrel, the operator depresses the starting handle 67, 20 first against the sole action of the spring 68 and upon further movement against the combined action of this spring and the leaf-spring 70. This draws the tie-rod 71 forward and rotates the clutch lever 73-73a 25 counterclockwise, which causes the cone member 32 to engage the rotating fly-wheel 31 of the motor 30. Power is thus transmitted through motor pinion 35, gear 36, sprocket 37, chain 38 and sprocket 39 to the driving-shaft 50 and mandrel 25 and causes these to rotate.

As the handle 67 is depressed the cam 222 of the latch 66 clears the end 72 of the latch-rod 54, as described, and allows the latter to move toward the left under the action of the spring 65. This locks the latch 222 and prevents the tie-rod 71 and lever 73 from returning to normal position.

With the shaft 50 thus rotating, the trip-block 51 progresses toward the right until its downward projection 48 engages the stop-collar 52, and in its further movement thus forces the tie-rod 54 to the right against the action of its spring 65. Retraction of the end 45 72 releases the latch-lever 66, and the spring 68 returns the latch-lever 66, handle 67 and tie-rod 71 to their normal position. The arm 73 being also returned to normal position, causes the cone 32 to disengage the fly-wheel 31 and to engage, with its right-hand face, the stationary floating brake-shoe 34. This arrests the driving-shaft 50 and thus stops winding of the condenser.

The number of turns of the condenser as 55 appears is thereby determined by the position of the stop-collar 52, which is shifted to obtain a selected number of turns and secured in such selected position by the locking-collar 53. To increase the number of turns the collar 52 is moved toward the right, and vice versa.

After the winding of a condenser is completed, to start winding of a subsequent condenser, the operator may return the trip-block 51 to its initial position by first disen-

gaging the pawl 58 by counterclockwise rotation of the handle 60 and then pressing the block towards left by means of this handle.

The handle 78 provided on the rod 54 enables the operator to manually stop winding 70 at any desired moment. By forcing, by means of the handle 78, the latch-rod 54 toward the right the latch is returned to its normal stop position in a similar way as through engagement of the trip-block extension 48 75 with the stop 52, which has been discussed previously.

The leaf-spring 70 provides for a soft and easy starting of the mechanism. The spring, as previously stated, does not press normally 80 against the latch cam 222, but only upon slight depression of the starting handle 67. In this position of the handle 67 the clutch members 31 and 32 are partially engaged, permitting a slipping action. If the operator further 85 depresses the handle 67, the face of cam 222 clears the end 72 of the latch-rod 54. This locks the latch 66 and brings the clutch members into full engagement.

The spring 76, which is adjustable by 90 means of the nuts 75, compensates for any wear of the clutch faces or slack motion that may result in the bearings or other portions of the device.

The winding speed may be changed either 95 by regulating the speed of the motor or by substituting the sprocket wheels 37 and 39 with wheels of different size.

A revolution counter 226 is preferably provided and is shown as being supported on 100 the pedestal 64 and driven by means of gears 227 and 228, from the shaft 50. This revolution counter is used for the setting of the stop collar 52 on the rod 54, as well as a check, but is not required in regular operation as it 105 is apparent that once the collar 52 is properly set, the required number of turns will be obtained automatically.

The cut-off and feeding mechanism (see 110 Figs. 1, 2, 7, 8, 11 and 12) comprises a carrier-frame 88 having two arms 260-260 connected by a flat rib 261, said frame being inclined toward the front and supported by means of a spindle 87, pivoted at one end in the frame 11 and on its other end in a bearing 253 of a 115 vertical end-plate 85. The carrier-frame 88 is subject to angular motion around the spindle 87 under conditions later to be described.

Fixedly connected with or forming integral part of the carrier-frame 88, is a cross-arm 251-252. Anchored to the rear extension 252 of the cross-arm is a coil-spring 89, the other end of which is anchored to the bed-plate 10 by means of an adjustable screw 255. The coil spring 89 tends to impart to the carrier-frame 88 a counterclockwise rotation and thus to lift its front end. To arrest such rotation of the frame, there is provided an adjustable stop-screw 90 carried by a lug 256,

connected with or forming integral part of the frame 88; the stopscrew 90 cooperates with a rotatable stop-block 91, provided with a spindle 258 which is pinioned in and projecting through the end-plate 85. The projecting end of the spindle 258 is provided with an operating handle 93. Normally, stop-block 91 lies with its shortest face against the stop-screw 90, as shown in Fig. 7; however, upon rotation of the handle 93 over an angle of 90 degrees the trip-block 91 confronts its longer face towards the screw 90, thus permitting the spring 89 to further rotate the frame 88 in a counterclockwise direction and thus further raise its front end for a purpose later to be described.

For clockwise rotation of the frame 88, and thus to lower its front end, there is provided an operating handle 95, which by means of a shaft 96, a lever 97 and a link 98, engages a stud 253a of cross-arm 251. Clockwise rotation of the handle 95 will cause similar rotation of the cross-arm 251, spindle 87 and the frame 88. The handle 95 is secured to the shaft 96 by an adjusting cap-screw 100 and the handle may be secured to the shaft in any desired angular relation convenient to the operator.

The clockwise rotation or downward movement of the carrier-frame 88 is limited by an adjustable stop-screw 101, supported by a bracket 101a affixed to the end-plate 85, against which the carrier-frame rib 261 comes to rest in its downward movement.

The two arms 260—260 of the carrier-frame 88 are slightly upwardly bent at their front end, and between these arms rotatably located on the spindle 87 is the main roller 22, which, as already stated, gathers the individual stock strips fed from the guide-rods 208, into a single composite strip. The ends of the arms 260 constitute bearings 260a for the feeder roller 23.

A double-armed swinging frame 103—103 provided with a cross member 265 is pivoted between the arms 260—260 in bushings 263—263 thereof by means of a spindle 275. The swinging frame arms 103—103 form at their end bearings 264—264 to carry the clamp roller 24.

A leaf-spring 105 affixed to the rib 261 of the frame 88 presses against the cross member 265 of the supplemental frame 103 and maintains normally the roller 24 pressed against the roller 23. Affixed to the right arm of the supplemental frame 103 is a cam-roller 106, which when the frame 88 is raised above the normal position engages a cam 107 affixed to the frame 11. (See Fig. 12.) This prevents the roller 24 from following the frame 88 and the roller 23 in their upward movement, and thus provides for a gap between the rollers 23 and 24 for the insertion of new stock. The raising of the frame 88 above its normal position, as has already

been stated, is obtained by the movement of the handle 93, so as to present the longer face of the stop-block 91 to the stop-screw 90.

By returning handle 93 to the position shown in Fig. 7, the carrier-frame 88 is returned to its normal position whereby the roller 23 again comes to rest on roller 24 and the latter through action of the leaf-spring 105 lightly clamps the paper between the two rollers. The stock and mechanism are now ready for winding operation.

I shall now proceed in describing the cut-off mechanism. This comprises a knife-guide consisting of an upper half 111 and a lower half 111a, the knife-guide being supported and affixed to on its left side to the top of the end-plate 85 and on its right side by means of a supporting brace 272 to the frame 11. In its central portion the knife-guide is provided with a slot for a serrated knife blade 110. Attached to or integral with the knife-blade 110 is a lug 273 pivoted by means of a pin 117 to a lever 112. The lever 112 is pivoted on its turn on a pivot 121 to the brace 272, the free end of the lever 112 being provided with a reduced portion 274 disposed within the extensions of a fork or yoke 275a of a yoke-arm 113, later to be described.

In the normal position of the cutting mechanism, as shown in Fig. 8, the portion 274 is retracted and rests against a stop-pin 118 provided on the top edge of the end-plate 85. The yoke-arm 113 is mounted on a spindle 119 pivoted on the end-plate 85, and is provided below its pivoting point with a short extension 276, to which is suspended a coil-spring 115, anchored with its other end to the end-plate 85. The spring 115 tends to rotate the yoke-arm 113 counterclockwise, thus retaining the knife-lever 112 in the position shown in Figs. 7 and 8. The yoke-arm 113 is also provided with a sector-shaped extension 280, having a correspondingly shaped slot 121.

Also mounted on the spindle 119 is an adjustable cam-lever 114, which carries on its upper end a flanged screw 120, passing through the slot 121 of the yoke-arm 113. The end-plate 85 is cut out corresponding to extension 280, thereby giving access to screw 120 to permit its adjustment; i. e. its shifting in the slot 121. The lower front end of the cam 114 is slightly upwardly curved and cooperates with the carrier-frame, as will be shown later on.

The yoke-arm 113 also carries a cam 116, which normally abuts against a roller 124 of the left-hand arm 260. The cam 116 retains the yoke-arm 113 and thus the knife 110 in its normal position and also returns it thereto whenever the carrier-frame 88 is returned to normal position, even should the spring 115 break or weaken. This safety feature safeguards against leaving the knife 110 un-

protected after the cutting operation has been completed.

Normally, the cutting mechanism assumes the position shown in Figs. 7 and 8. If, however, after completion of the winding of a condenser the material is to be severed, the operator actuates the handle 95, which rotates frame 88 in clockwise direction by means previously described. At the same time the operator holds the hand-wheel 130 preventing the mandrel 25 from rotating; with the result that the downward swing action of the frame 88 throws out stock material from the rolls *a*-1, *a*-2, etc.

At the same time the frame 88 also approaches the composite strips to the edge of the knife-blade 112, and when during the tilting of frame 88 the roller 124 comes to engage the curved lower end of the cam 114, it causes clockwise rotation of this cam and of the yoke-arm 113, and causes the latter to force, by means of its lug 275a pin 274 and lever 112, the knife 110 to project through the slot of the guide 111 and to sever with its serrations the wound condenser from the rest of the stock.

When the front end of the carrier frame 88 is lowered by actuation of the handle 95 as above described, and the hand-wheel 130 held fast to prevent rotation of the mandrel, stock is drawn from the rolls without being wound on the mandrel. After the knife 110 severs the wound condenser from the stock rolls and the carrier frame is returned to its normal position, the drawn-out stock projects and hangs loosely from between the rollers 23 and 24. The length of the drawn-out stock corresponds to the length of the arc which the clamping edge of the rollers 23 and 24 describes when these rollers move from their normal into their lowermost positions. These two positions of the rollers are so selected that the length of the drawn-out stock is sufficient, without additional manual drawing of material, to begin the winding of a new condenser when the carrier frame has returned to its normal position.

In case the diameter of the winding mandrel is changed the arc of swing between the normal and lowermost position of the carrier frame 88 has to be changed accordingly by means of the adjustable stop-screw 101. At the same time, however, it is also required to slightly change the position of the knife cam 114 in its relation to the yoke 113, this being done by shifting the adjusting cap-screw 120 in the slot 121.

The clamp rollers 23 and 24 retain the stock in proper alignment to each other and to the winding mandrel, both during cutting as well as in starting the winding of a new condenser.

While I have described and shown a specific structure to illustrate my invention, it should be well understood that various

modifications suggest themselves to those skilled in the art without departing from the scope of my invention, and therefore the appended claims should be construed as broad as allowed in view of the prior art.

The term, manual operation, in the claims should be construed also to include foot-operation.

What I now claim as new and desire to secure by Letters Patent, is:

1. In a winding apparatus for electrical condensers, a frame and stock-roll carrying spindles mounted thereon, a winding mandrel and means to feed and guide the stock from the spindles to the mandrel said means including a rotatable feeding frame, manual means to start rotation of the mandrel and automatic means to stop such rotation after a predetermined number of revolutions, and means to rotate the feeding frame relative to the mandrel to advance the stock for the winding of a subsequent condenser and to sever the wound stock from the stock roll.

2. In a coil winding mechanism, a feeding frame over which the stock is fed, a winding mandrel and manual means to start rotation of said mandrel, automatic means to stop such rotation after the coil has been wound to a predetermined number of turns, manual means to arrest said mandrel independently of the automatic stopping means, and manually initiated means to rotate the feeding frame relative to the winding mandrel and to sever the wound condenser from the winding stock and automatically advance stock of sufficient length to start winding of a subsequent coil.

3. An automatic control device for winding apparatus, comprising a winding shaft and a driving motor, clutch mechanism interposed between said motor and said shaft and a member advancing along said shaft when said shaft is rotated, an operating handle which, when placed in an operative position causes the clutch to engage and the motor to drive the shaft, automatic means maintaining the handle in its operative position, and means to return the handle from its operative position and disengage the clutch after said member has advanced a predetermined distance along said shaft.

4. In a winding apparatus, a normally revolving motor and a normally stationary winding shaft, a member advancing along said shaft when the shaft is rotated, means under the control of the operator for connecting said shaft with said motor, automatic means for subsequently interlocking and maintaining such connection, and automatic means for unlocking such connection after said member has advanced a predetermined distance, and means to abruptly stop revolution of the mandrel upon actuation of said unlocking means.

5. In a winding apparatus a cutting and

feeding device, comprising a pivotally-mounted frame having a plurality of positions, including an intake, a winding and a cutting position, and resilient means to maintain said frame in the intake and winding positions.

6. In a winding apparatus stock feeding and cutting means, comprising a rotatable feeding frame and means to maintain said frame in a normal position, a cutting device, and means under manual control to move the frame and approach the stock to the cutting device, and simultaneously advance the stock for the beginning of a new condenser, and to subsequently sever the stock through actuation of the cutting device.

7. In a winding apparatus stock feeding means comprising a feeding frame, and cutting means normally inactive, clamping rollers for the stock carried by said frame, the stock being normally clear from the cutting device and brought in proximity thereof upon manual movement of the frame, said movement also actuating the cutting means to sever the stock.

8. In a condenser winding machine a cutting and feeding device, including a rotatable stock feeding frame, means to maintain said frame in normal position, a serrated knife and a guide therefor, and manual means to rotate the frame to cause the knife to project from the guide and to sever the stock, and means to retain the knife in its guide when the frame is in its normal position.

9. In a winding apparatus, in combination a feeding frame and normally inactive cutting means, and manual means to rotate the feeding frame and actuate the cutting means upon rotation of said frame.

10. In a winding apparatus, in combination a feeding frame and normally inactive cutting means, means to rotate the feeding frame into a cutting position and actuate the cutting means upon such rotation, and means to adjustably vary said cutting position of the feeding frame and to correspondingly vary the position of said cutting means.

11. In a winding apparatus, a stock cutting machine including a cutter blade and a frame and a manually operated handle to rotate the frame and approach the stock to the cutter blade, and means effective upon rotation of said frame to advance the blade toward the stock for automatic severance thereof.

55 Quincy, Mass., Dec. 12, 1929.
FRANK DESMOND SPRAGUE.
